W. H. BAYNARD

SHOE HEATER

Filed Dec. 12, 1921

FIG. 2 -

FIG. 3 -

FIG. 1 -

FIG. 4 -

INVENTOR:

WILLIAM H. BAYNARD

by Wright & Son, Quincy, Mass

ATTVS

UNITED STATES PATENT OFFICE.

WILLIAM H. BAYNARD, OF QUINCY, MASSACHUSETTS, ASSIGNOR TO HARRY H. BECKWITH, OF BROOKLINE, MASSACHUSETTS.

SHOE HEATER.

Application filed December 12, 1921. Serial No. 521,758.

To all whom it may concern:

Be it known that I, WILLIAM H. BAYNARD, a citizen of the United States, residing at Quincy, in the county of Norfolk and State 5 of Massachusetts, have invented new and useful Improvements in Shoe Heaters (Case A), of which the following is a specification.

In the manufacture of shoes it is common practice to insert stiffening members between 10 the upper and lining at certain parts of the shoe, for example, at the toe. These members are often composed of sheet material treated, impregnated, or coated with asphaltic or resinous materials which may be softened by the application of heat, or heat and 15 moisture, so that they may conform to the configuration of the last and then be allowed to harden to retain the shape imparted. In practice it is usual to soften these stiffeners twice, first, after the portions of the shoe 20 have been assembled and before the upper has been pulled over the last, and second, between the pulling over and final lasting operations.

25 The present invention relates to a construction more particularly adapted and designed to effect the first heating operation. The stiffener as assembled in the toe is substantially flat and the upper is attached to 30 the last only at the heel. The toe portion may therefore be laid on a support where it may be subjected to heated vapor while the toe of the last extends beneath the support.

35 One feature of this invention relates to the construction of support by which a sheet of fabric is held beneath the shoe upper, the vapor passing through the fabric.

40 A further feature relates to improved vapor producing and distributing means by which vapor is supplied to the lower face of the fabric.

45 Further features and advantageous details of construction and combinations of parts will appear from a more complete description of the embodiment shown in the drawings in which—

Figure 1 is a plan of a heater partly broken away.

50 Figure 2 is a section on line 2—2 of Figure 1.

Figure 3 is a section on line 3—3 of Figure 2.

Figure 4 is a diagram of the electrical wiring.

Referring to these figures at 1 is indicated 55 a base in the form of a shallow pan for supporting the heater. The heater comprises an elongated receptacle 2 having a comparatively deep trough portion 3 along one side and a shallow basin portion 4 extending parallel thereto. The trough portion 3 is substantially circular in cross section and extending therethrough and nearly filling this portion is a pipe 5 made fast at its ends in the end walls of the receptacle to 60 make a fluid tight joint therewith. Substantially centrally of the length of this receptacle is a lateral extension 6 formed as a general triangularly shaped open topped pan having a rounded apex. The side walls of 70 this pan are formed by a marginal upwardly extending flange 7 to which is made fast at the apex of the pan a bracket 8 carrying at its top a support 9 having an upwardly extending marginal flange 10. As shown this flange is formed ring shape and is intended 75 to serve as a retainer for the lower end of a similarly shaped water reservoir from which water may be led into the pan. A pipe 11 passes up through the bottom of the pan at 80 one end and at its other end up through the bottom of the receptacle 2 opening beneath the pipe 5. By this means the water is conducted from the pan to the trough portion of the receptacle.

85 The basin portion 4 is formed with a base member 12 which extends toward the top of the trough 3 at a gradual upward inclination, while the outer edge of the portion 12 is turned upwardly as shown at 13. The 90 rear wall of the trough portion extends upwardly considerably above the member 12 as shown at 14, and extending over the wall 14 and the outer edge 13 of the basin is a fabric of canvas or the like 15. The forward end of this canvas is turned under the base plate 12 and is formed with a looped edge through which passes a retaining rod 16 which is supported in any suitable manner preferably at its ends in portions of the member 2. The opposite end of the fabric is looped about a bar 17 which may be passed beneath a pair of lugs 18 extending outwardly and rearwardly from the wall 14 and through

- which are threaded adjusting bolts 19 which bear on the ends of the bar 17. By turning down these bolts the bar 17 may be lowered, increasing the tension on the fabric.
- 5 In order to support this fabric against undue sagging it is preferable to place therebeneath a support preferably formed of a wire netting or other foraminous material 20 which is curved downwardly at its forward edge at 21 to rest on the upper surface of the base plate 12 and at its rear end it is bent downwardly into engagement with the upper surface of a baffle plate 22. This baffle plate is positioned directly above the trough 3 and is forwardly and downwardly inclined so that vapor arising from the trough is directed forwardly to mingle with vapor arising from the basin. The support 20 holds the fabric out of contact with the plate 22 so that vapor may pass freely therebetween.

The vapor is produced in the trough by means of any suitable form of heater, as herein shown an electric heating element 25 being employed. This element extends through the pipe 5 and one end is connected to a wire 26 leading to a lamp socket 27 and to a switch 28. The other end of this heating element has attached thereto a wire 29 which extends through a pipe 300 positioned substantially beneath the bar 17 and supported in bracket ears 31 extending rearwardly at opposite ends of the member 2. After passing through this pipe the wire 29 leads to the lamp socket 27 and switch 28. At 30 is shown a lamp held by the socket 27. As shown in Figure 4 the lamp 30 is shunted across the wires 26 and 29 and furnishes a visible indication as to whether or not the heater is in operation.

Positioned forwardly of the base member 1 is a shoe support 35 which inclines upwardly away from the heater. This support has an upwardly directed flange portion or guard 36 against which the toe end of the last may rest as shown in Figure 2 so that the toe of the last may be kept out of contact with the heater and protected from the heat therefrom by which it might be liable to be injured. As shown in Figure 2 the toe of a shoe may be supported on the member 35, the last extending under the basin 21 and the upper, together with the stiffener assembled therein, being laid on the upper face of the fabric. If now the water in the trough be heated by the electric heating element some of this water may boil over and fill the basin 21. Steam arising from the trough is deflected by the plate 22 forwardly, and mingles with the steam arising from the water boiled into the basin. The steam from both sources then finds its way through the foraminous support and the fabric to the under side of the shoe upper

where it may act to soften the stiffener. The comparatively small water-receiving capacity of the trough causes the water to be boiled quickly so that no material delay is occasioned in starting the apparatus, 70 while the presence of the basin serves to supply a cooler vapor which tempers the severity of the heat. The baffle plate 22 causes the vapors to be thoroughly mixed and causes a substantially even distribution of 75 the vapor over the fabric so that the tempering and softening of the shoe upper is uniformly effected.

Having thus described an embodiment of this invention it should be evident that many 80 changes and modifications might be made therein without departing from its spirit or scope as defined by the appended claims.

I claim:

1. In a shoe heater, a trough, a heating 85 element extending longitudinally in said trough, a shallow basin extending along one side of said trough in position to receive water boiled over from said trough, and a support for a shoe part positioned above 90 said basin.

2. In a shoe heater, a trough, a heating element extending longitudinally in said trough, a shallow basin extending along one side of said trough in position to receive water boiled over from said trough, means 95 for deflecting steam from said trough over said basin, and a support for a shoe part positioned above said basin.

3. In a shoe heater, a trough, a heating 100 element extending longitudinally in said trough, a shallow basin extending along one side of said trough in position to receive water boiled over from said trough, means for deflecting steam from said trough over 105 said basin, and a foraminous support for a shoe part positioned above said basin.

4. In a shoe heater, a trough, a heating element extending longitudinally in said trough, a shallow basin extending along one 110 side of said trough in position to receive water boiled over from said trough, means for deflecting steam from said trough over said basin, and a fabric covering said trough and basin. 115

5. In a shoe heater, a receptacle having a trough along one side and a shallow basin at one side of said trough, and a fabric covering for the top of said receptacle.

6. In a shoe heater, a receptacle having a trough along one side and a shallow basin at one side of said trough, a fabric covering for the top of said receptacle, bars to which opposite marginal portions of said fabric are fastened, and means for supporting said bars on said receptacle. 125

7. In a shoe heater, a receptacle having a trough along one side and a shallow basin at one side of said trough, a fabric covering for the top of said receptacle, bars to which 130

- opposite marginal portions of said fabric are fastened, and means for supporting said bars on said receptacle, one of said bars being adjustable to adjust the tension of 5 said fabric.
8. In a shoe heater, an open topped receptacle having a trough along one side, and a shallow basin adjacent said trough, a heating element in said trough, means to supply 10 water to said trough to be heated by said element and to be boiled over into said basin, a baffle above said trough to direct vapor therefrom to mingle with vapor from the water in said basin, and a fabric stretched 15 over the top of said receptacle and on which articles may be laid.
9. In a shoe heater, an open topped receptacle having a trough along one side, and a shallow basin adjacent said trough, a heating 20 element in said trough, means to supply water to said trough to be heated by said element and to be boiled over into said basin, a baffle above said trough to direct vapor therefrom to mingle with vapor from the 25 water in said basin, a fabric stretched over the top of said receptacle and on which articles may be laid, and means to hold said fabric out of contact with said baffle.
10. In a shoe heater, an open topped receptacle having deeper and shallower portions, a heating element in said deeper portion, means to conduct water about said element where it may boil over into said shall-
- lower portion, means to mingle the vapors from said portions, and a foraminous cover 35 for said receptacle for supporting articles to be treated.
11. In a shoe heater, an open topped receptacle having deeper and shallower portions, a heating element in said deeper portion, means to conduct water about said element where it may boil over into said shallower portion, a baffle for deflecting vapor from one of said portions to mingle with vapor from the other of said portions, a 40 foraminous member spaced above said baffle, and a fabric covering the top of said receptacle and resting on said member.
12. In a shoe heater, a receptacle having a substantially flat fabric covering for supporting a shoe part, and means for tensioning 45 said covering.
13. In a shoe heater, an open-topped receptacle, a fabric covering overlying said open top, bars to which opposite edges of 50 said fabric are made fast, and means for relatively adjusting said bars to tension the fabric over said receptacle.
14. In a shoe heater, a support for a shoe part comprising a substantially flat fabric, and means for holding said fabric under tension.

In testimony whereof I have affixed my signature.

WILLIAM H. BAYNARD.
